UNITED STATES PATENT OFFICE.

ISIDORE PANES, OF NEW YORK, N. Y.

BRASSIÈRE.

Application filed September 30, 1920. Serial No. 413,733.

To all whom it may concern:

Be it known that I, ISIDORE PANES, a citizen of the United States, and a resident of the city of New York, borough of the Bronx, county of Bronx, and State of New York, have invented a new and Improved Brassière, of which the following is a full, clear, and exact description.

This invention relates to clothing and particularly to the improved combined brassière and camisole and has for an object to present a construction wherein the garment may be quickly and easily applied or removed by the person using the garment.

Another object of the invention is to provide a brassière with the securing means spaced from the sides a sufficient distance to allow easy operation by the person using the device, while at the same time presenting means which will hide or cover the securing members.

A still further object of the invention is to provide a brassière having an opening near the front and a plurality of spaced rows of securing members together with a flap fastening member for covering the securing means so as to present a continuous smooth surface at the front of the garment.

In the accompanying drawing—

Figure 1 is a perspective view showing part of a figure with a garment disclosing an embodiment of the invention applied thereto.

Figure 2 is a fragmentary plan view showing adjacent ends of the brassière together with the securing members.

Figure 3 is a view the same as shown in Figure 2 but with the flap in a closed position.

Referring to the accompanying drawing by numerals 1 indicates the body of the brassière which is provided with shoulder straps 2 and 3 of any desired kind. In order to present a combined brassière and camisole structure, the body 1 is made of strong material but of comparatively ornamental material to give the desired ornamental effect of a camisole while the strength of the material will permit it to act as a brassière for properly shaping up the person using the device.

The garment illustrated includes a section 5 secured to one end of the body 1 along a substantially vertical line indicated at 4 and extending forwardly in such manner as to be adapted to be overlapped by the other end portion of the body when the garment is in closed position, as illustrated in Fig. 3.

The overlapping end portion of the body 1 is denoted in the drawings by the numeral 6. The flap 5 serves as a connecting member, as will presently appear.

In using the brassière it is necessary to provide comparatively strong securing means for holding the brassière clamped reasonably tight to the body and in order to secure this result a strip 7 having hooks 8 is secured to body 1 an appreciable distance back of the free end of the portion 6 thereof, said hooks co-acting with the rows of eyes 9 and 10 preferably provided on suitable strips connected to the section 5. When the camisole is first put on, the hooks 8 may be engaged with the eyes 9 and if the garment properly fits the portion 6 turned over from the position shown in Figures 1 and 2 to that shown in Figure 3 and the elastic tab 11 stretched until socket 12 connected therewith may be snapped on the stud 13 secured to the body 1 at a convenient point under the arm. This will effectively hold the portion 6 in place and give a smooth continuous appearance to the garment on the front and sides. The back of the garment is preferably made of the same material as the front and is of suitable shape.

In case the garment is somewhat loose after hooks 8 have been engaged with the eyes 9 they are moved over to eyes 10 which will draw in the garment more tightly. The tab 11 is then placed in position as just described for holding the portion 6 in place. It will be noted that the portion 6 of the body is used principally as an ornamental covering for the section 5 and associated parts and, consequently does not need any strong securing means for holding the same in place, though the hooks and eyes 8, 9 and 10 are very desirable because considerable strain is brought to bear thereon. In the drawing only two rows of eyes are shown but more could be provided if desired or even less though ordinarily an adjustment of two or three rows is preferable. If the size of the person is beyond the adjustment of a particular garment a different size garment must be provided.

In applying the garment the shoulder straps 2 and 3 may be disengaged from the front of the body 1 if removably connected therewith and the body placed in position and hooks and eyes engaged. If the shoulder straps 2 and 3 are connected permanently to the body 1 the person usually

places one arm through shoulder strap 2 and then moves the other strap over the head to a proper position on the shoulder after which the garment is pulled in as tight as desired and the desired eyes engaged with the various hooks 8. The portion 6 of body 1 is then fastened in place by connecting a snap fastener or sockets and studs 12 and 13. Preferably there is only one snap fastener as the elastic member 11 will accommodate itself to the different positions of the rows of hooks 8 though if desired a number of studs 13 could be provided or a number of independent complete snap fasteners.

What I claim is:—

1. A garment of the character described comprising a body having separate side edges and being adapted to be arranged to encircle the body of a wearer so that the side edge of the back portion thereof is positioned under one arm of the wearer and the side edge of the front portion thereof is positioned adjacent to the first edge, a section secured to the body along the first side edge thereof and extending toward the front beyond the second side edge of the body in underlying relation to the adjacent portion of the latter, a substantially vertical row of fastening elements connected to said extending section adjacent to the free end thereof, a row of fastening elements attached to the under side of the portion of the body overlapping said section at an appreciable distance from the free end of said portion of the body and being engageable with the first row of fastening elements, and means for holding said overlapping portion of the body in place over said extending section and in position to cover said fastening elements, said means comprising an elastic tab at-

tached to the overlapping portion of the body and having a fastening element thereon and a cooperating fastening element on the back portion of the body.

2. A garment of the character described comprising a body having separate side edges and being adapted to be arranged to encircle the body of a wearer so that the side edge of the back portion thereof is positioned under one arm of the wearer and the side edge of the front portion thereof is positioned adjacent to the first edge, a section secured to the body along the first side edge thereof and extending toward the front beyond the second side edge of the body in underlying relation to the adjacent portion of the latter, a row of fastening elements connected to said extending section adjacent to the free end thereof, and row of fastening elements attached to the under side of the portion of the body overlapping said section at an appreciable distance from the free end thereof and being engageable with the said row of fastening elements.

3. A garment of the character described, adapted to encircle the body of a wearer and opening along a substantially vertical line located approximately midway between the vertical median line of the garment front and a vertical line extending under one arm of the wearer, said garment including an overlying flap portion extending from said vertical line of opening toward the vertical line under the arm of the wearer and terminating adjacent to the latter, means for releasably holding the garment closed along said line of opening, and other means for holding the flap portion closed, whereby the garment when in fully closed position will be smooth and unbroken across the front.

ISIDORE PANES.
